Primary Examiner — Garth Rademaker*Assistant Examiner* — Melanie Pellegrini(74) Attorney, Agent, or Firm — Andrus Intellectual Property Law, LLPCLAIM

The ornamental design for a charm, as shown and described.

DESCRIPTION

FIG. 1 is a top view of a charm;

FIG. 2 is a bottom view thereof;

FIG. 3 is a front view thereof;

FIG. 4 is a back view thereof;

FIG. 5 is a left side view thereof;

FIG. 6 is a right side view thereof;

FIG. 7 is a perspective view thereof, showing the charm applied to a cap of a bottle; and,

FIG. 8 is a perspective view thereof, showing the charm on a chain.

The broken lines in FIGS. 7 and 8 showing a bottle and a chain, respectively, are for purposes of illustrating the environment in which the charm embodying the design may be used; the broken lines form no part of the claimed design.
